GATE LOCK

John Lamach, Billings, Mont.

Application July 29, 1944, Serial No. 547,178

3 Claims. (Cl. 298—23)

My invention relates, in general, to the art of closure fasteners and it especially relates to end gate locks for dump vehicles.

Primarily the invention has for an object to provide a simple rugged device for securing a hinged closure to a body in such manner that movement between the closure and the body at the locked area will be effectively prevented.

A further object is to provide end gate locks for a dump type vehicle, for holding the free edge of a hinged gate firmly secured to each side wall of the vehicle so that the end gate will serve as a cross brace between the upper parts of the side walls.

A still further object is to provide a fastener that can be used in all places where a fastener of its kind can be employed, it being designed particularly for use upon portable machinery, such as trucks, to hold the end gates thereof securely in place regardless of the amount of material within the truck which may press against it (i. e. the pressure of the material will not affect the operation of the lock which can therefore be easily operated regardless of the weight against it).

Again it is an object to provide a means for securing an end gate in closed position in such manner that it will not rattle.

Other objects will in part be obvious and in part be pointed out hereinafter.

To the attainment of the aforesaid objects and ends the invention also resides in those novel details of construction, combinations and arrangements of parts all of which will hereinafter first be fully described and then be specifically pointed out in the appended claims, reference being had to the accompanying drawing in which:

Fig. 1 is a rear elevation of a portion of a vehicle with an end gate, showing one of the two locks employed to secure the gate in closed position.

Fig. 2 is a detail elevation of a portion of the same looking in the direction of the arrow in Fig. 1.

Fig. 3 is a detail horizontal section on the line 3—3 of Fig. 1.

Fig. 4 is a detail rear elevation showing the angle-bracket which carries the locking device.

In the drawing in which like numerals of reference indicate like parts in all the figures, 1 represents the rear cross sill of the vehicle, 2 the floor and 3 the side walls. In the structure illustrated the side walls 3 and the door 8 are constructed of sheet metal. To the ends of the

sill are secured at 4, hollow posts 4 having flanges 5 which are welded to the sides 3.

Metal plates 6 are welded to the upper rear ends of the wall 3 and the outwardly angled flange 3a of the same. These plates 6 (one at each side of the vehicle) have holes 7 for the reception of dowel pins 17 carried by striker plates 15, which plates are securely welded to the upper corners of the door 8. The door 8 is dished, as at 9, to fit within the body opening and it has a marginal flange 10 as shown in Figs. 1 and 3.

The door 8, of sheet metal, is suitably hinged to the sill 1, as for instance by hinges whose straps 11 are looped back as at 12 and secured at 11a to the door. The other elements 14 of the hinges carry pins 13 that pass through the portions 12 of the straps as indicated in Fig. 1. The striker plates 15 each have their outer edges bent at approximately right angles as at 16 for a purpose presently to appear.

At each side of the vehicle and adjacent but in front of the posts 4, there are angle-brackets 18, secured at 19 to the sides 3. These brackets 18 have holes 20 for the passage of eye-bolts 21.

Pivoted at 23 to the eyes of the bolts 21 are pairs of angle links 22. The angled ends of these links, when the gate is locked, project over the ends 16 of the plates 15 and carry pivots 25 for the locking levers 24. When in the locking position (Figs. 1 to 3), the pivot axis 25 of the device lies directly to the rear of the dowel 17 (see Fig. 3), while the pivot 23 lies to the outer side of the same.

Each locking lever 24 has a nose 26 which engages the plate 15 at a point between pivots 25 and 23 and when locked, engages the lip formed by the bent portion 16 of the plate. The long arm of the lever 24, in the locked position lies flat against the plate 15.

Coil springs 27 on the forward portions of the eye-bolts 21, and locked nuts 28 serve to supply the required tension in the direction of the parallel arrows in Fig. 3 to keep the gate locked.

To unlock the gate the levers 24 at each side of the gate are pulled in the outward direction (see curved arrow x in Fig. 3), until the pivots 25 pass to positions between noses 26 and pivots 23 (noses 26 acting as the fulcrums) whereupon the springs 27 will pull the links against the angle-brackets 18 as stops. The gate 8 may now be swung down on its hinges.

From the foregoing description taken in connection with the accompanying drawing it is thought the construction, operation and advan-

tages of my invention will be clear to those skilled in the art.

What I claim is:

1. In combination with a body having a transverse wall and two side walls, and a closure hingedly connected to said transverse wall and adapted to fit between said side walls when in closed position: dowel-carrying plates rigidly secured to opposite sides of said closure at places remote from the hinge connection and overlapping said side walls; plates secured to said side walls to lie normal thereto; said last named plates having holes to receive said dowel pins; and latches mounted on the body sides and having means to engage the dowel-carrying plates to hold the dowels in the said holes.

2. In combination with a body having a transverse wall and two side walls, and a closure hingedly connected to said transverse wall and adapted to fit between said side walls when in closed position: dowel-carrying plates rigidly secured to opposite sides of said closure at places remote from the hinge connection and overlapping said side walls; plates secured to said side walls to lie normal thereto; said last named plates having holes to receive said dowel pins; brackets secured to the said sides; spring loaded I bolts mounted in said brackets and disposed parallelly to said sides in the longitudinal direction of the same; said dowel-carrying plates having lips and levers having toes for engaging said lips; angle links pivoted to said I bolts and to said levers and extending over the ends of said walls and closure when in locked position by virtue of all of which the dowels will be held in their holes and the closure will constitute a cross brace between the side walls.

gaging said lips; angle links pivoted to said I bolts and to said levers and extending over the ends of said walls and closure when in locked position by virtue of all of which the dowels will be held in their holes and the closure will constitute a cross brace between the side walls.

3. In combination with a body having a transverse wall and two side walls, and a closure hingedly connected to said transverse wall and adapted to fit between said side walls when in closed position: dowel-carrying plates rigidly secured to opposite sides of said closure at places remote from the hinge connection and overlapping said side walls; plates secured to said side walls to lie normal thereto; said last named plates having holes to receive said dowel pins; brackets secured to the said sides; spring loaded I bolts mounted in said brackets and disposed parallelly to said sides in the longitudinal direction of the same; said dowel-carrying plates having lips and levers having toes for engaging said lips; angle links pivoted to said I bolts and to said levers and extending over the ends of said walls and closure when in locked position by virtue of all of which the dowels will be held in their holes and the closure will constitute a cross brace between the side walls.

JOHN LAMACH.
